UNITED STATES PATENT OFFICE.

WILLIAM H. INSLEY AND ALVIN C. RASMUSSEN, OF INDIANAPOLIS, INDIANA, AS-SIGNORS TO INSLEY MANUFACTURING COMPANY, OF INDIANAPOLIS, INDIANA, A CORPORATION OF INDIANA.

HOISTING APPARATUS.

Application filed January 6, 1921. Serial No. 435,325.

To all whom it may concern:

Be it known that we, WILLIAM H. INSLEY and ALVIN C. RASMUSSEN, citizens of the United States, residing at Indianapolis, in 5 the county of Marion and State of Indiana, have invented a new and useful Hoisting Apparatus, of which the following is a specification.

In that type of building-material-hoisting apparatus which comprises a mast, as distinguished from a tower, the earlier form was of such character that the mast could not be guyed at intermediate points; the bridge pan was carried by the hoisting 10 bucket and in its operation required a greater amount of power than was required in the main hoisting of the bucket, so that, merely for this bridge pan operation, a larger power unit was required; and the hoisting bucket 15 could not be readily detached from the mast so that the apparatus was practically limited in its use to the handling of fresh concrete mixture.

The object of our present invention is to 20 improve various details of construction, so that the mast may be guyed at intermediate points without interfering with the vertical movement of the hoisting member; so that the bridge pan may be operated without the 25 expenditure of much power, thereby permitting the use of smaller power unit and an operation of the bridge pan at slow speed; and so that interchangeable load-carrying members, such, for instance, as an automatically discharging bucket for handling concrete, a platform suitable for the reception 30 of loaded wheel barrows, etc., may be readily associated with and disassociated from the mast and hoisting cable.

40 The accompanying drawings illustrate our invention. Fig. 1 is a side elevation of our improved plant, showing the hoisting bucket in raised position; Fig. 2 a fragmentary side elevation of the hoisting bucket, bridge pan and adjacent parts; Fig. 3 a horizontal section on line 3-3 of Fig. 2; Fig. 4 a section on line 4-4 of Fig. 3; Fig. 5 a side elevation similar to Fig. 2 showing an elevator platform suitable for the reception 45 of wheel barrows and other loads; Fig. 6 a section on line 6-6 of Fig. 2; and Fig. 7 a section on line 7-7 of Fig. 5.

In the drawings, 10 indicates a mast of suitable height, supported at its bottom by

a step 11, and at its top by guy wires 12. 55 At suitable intermediate points, depending upon the total height of the mast, we arrange short channel sections 13 alongside the rear face of the mast and to these sections 13 may be attached suitable guy wires 14. 60

Along each front corner of the mast, we arrange an angle iron 15 which extends from top to bottom of the mast, thus providing laterally-extending flanges or tracks for the reception of clamping members or rollers, as 65 will be described.

Near the upper end of the mast, we arrange a header frame which comprises a gibbet arm 20 provided at its inner end with clamping plates 21 which take in behind flanges 15 and are held in place by bolts 22 passing through flanges 15. The gibbet arm 20 is provided at its outer end with a depending frame 23 which is provided at its lower end with a small hopper 70 24, a horizontally-arranged flange 25 adapted to receive a support or pivot pin 26 of the hopper end 27 of the first chute section. 75

Pivoted at 28, 28, on the frame 23 are two parallel links 29, 29, the outer ends of 80 which are pivoted to the bridge pan 30. Pivoted to the outer end of each upper link 29 is a link 31 which is pivoted at its upper end to a lever frame 32 pivoted at 33 on frame 23. 85

The hoisting bucket for mush concrete comprises a main body 40, having a hopper bottom 41, provided with a downwardly-inclined discharge spout 42, which has an arc-shaped end 43 preferably just within the 90 adjacent dimensions of the main body of the bucket.

Pivoted at 44 on spout 42 is a controlling gate 45 formed to cooperate with the arc-shaped end 43 of spout 42. Pivoted at 46 95 upon each side of the gate 45 is a link 47, the upper end of which is pivoted to lever 48, fulcrumed at 49 on bucket 40 and having its upper end extended above the bucket, in such way that at the upper end of its 100 movement, it will come into contact with the gibbet arm 20 and be depressed thereby as the bucket moves upwardly. The bucket 40 is provided with a hoisting bail 50, to which hoisting cable 51 is attached, said cable being 105 carried up over suitable pulleys 52 at the upper end of the mast and from thence to a suitable power plant 53.

As the bucket is lowered from the position shown in Fig. 1, the weight of pan 30 and its connected parts, is sufficient to carry it to the position shown in dotted lines and 5 in this position its receiving end is sufficiently distant from the adjacent portion of the bucket to permit adequate clearance. As a consequence, the bucket, in its upward movement, will clear the hopper 24 and the 10 bridge pan 30. As it nears the upper end of its stroke, bucket 40 will come into contact with lever 32 and will raise and project the bridge pan 30 to position shown in full lines in Figs. 1 and 2, the amount of force 15 required being merely sufficient to raise the weight of the parts and, as a consequence, the bucket 40 may be brought slowly to its final position.

At about the time the bridge pan 30 is 20 projected far enough to thoroughly receive the discharge from spout 42, lever 48 comes into contact with the gibbet arm 20 and gate 45 is lifted, so that the contents of the bucket will be discharged across pan 30 into 25 hopper 24 and from thence to hopper 27 and the connected chute section.

At each rear upper corner of the bucket 40, we provide a rearwardly-projecting flange 60 flush with the side of the bucket. 30 Adjacent each flange 60 and parallel therewith, is a rearwardly projecting flange 61, provided with a rearwardly open notch 62.

The plate 63 adapted to be bolted by bolt 64 to flange 60 and the adjacent portion of 35 the body 40, carries a bearing sleeve 65 at right angles to flange 60, and this bearing sleeve at its outer end carries a vertical plate 66 which may be bolted by bolts 67 to flange 61, the shaft 68 entering and lying within 40 slot 62.

Shaft 68 of a wheel 69 is journaled in the bearing sleeve 65 and contacts with the rear face of flange 15.

The angle irons 61 are bolted to the main 45 body of hopper 40 and at their lower ends are extended down some distance below the main body 40 of the bucket.

At the lower end of each angle iron 61 we secure a channel 70, in which is journalized shaft 71 of a roller 72, said roller contacting with the forward face of the adjacent flange 15.

Adjacent each roller 72 we attach to angle iron 61 an angle 73, one arm of which is 55 arranged parallel to the axis of the wheel 72 and overlaps the adjacent arm of angle 15, the arrangement being such as to prevent accidental displacement of the bucket structure, relative to the mast. However, 60 by removing angles 73 and by removing bolts 64, so that the roller structure 63-69 may be bodily removed, the hoisting bucket may be readily separated from the mast and a different load-carrying member substituted, for instance, a hoisting platform 80,

provided with rollers 69 and 72, like those already described and cooperating with the angles 15 in the same manner, may be provided for the handling of wheel barrows or dry loads of any kind, said platform 80 being provided with a hoisting bail 81 or any other suitable member, to which the hoisting cable may be attached, the connection being preferably such that the load will be fairly well balanced on the cable. 75

It will be readily understood that the substitute load-carrying members may take many different forms, depending upon the character of the loads to be carried, without departing from our invention. 80

We claim as our invention:

1. An apparatus for handling building materials comprising a mast, an arm carried by said mast near its upper end and provided with a depending frame, a chute hopper supported by said frame, an elevator bucket carried by the mast and provided with means for control of material therefrom, a bridge pan supported by the depending frame normally out of line of movement of the bucket upon links pivoted to the depending frame, and means controlled by the vertical movement of the bucket for projecting and retracting the bridge pan, said means comprising a lever projected into the path of movement of the bucket and a connection between lever and pan. 90

2. An apparatus for handling building materials comprising a mast, an arm carried by said mast near its upper end and provided with a depending frame, a chute hopper supported by said frame, an elevator bucket carried by the mast and provided with means for control of material therefrom, a bridge pan supported by the depending frame normally out of line of movement of the bucket, and means controlled by the vertical movement of the bucket for projecting and retracting the bridge pan. 100

3. An apparatus for handling building material comprising a mast, a load-carrying member mounted upon said mast for vertical movement thereon, the mast and load-carrying member having readily separable interengaging parts which leave the rear portion of the mast free for the attachment of guy wires at intermediate points permitting vertical movement of the load-carrying member and normally preventing lateral separation. 110

4. An apparatus for handling building material comprising a mast, a load-carrying member mounted upon said mast for vertical movement thereon, the mast and load-carrying member having interengaging parts which leave the rear portion of the mast free for the attachment of guy wires at intermediate points, permitting vertical movement of the load-carrying member and normally preventing lateral separation. 125

5. An apparatus for handling building materials comprising a mast, laterally projecting vertical tracks carried by said mast and spaced from the rear side of said mast so as to leave the same clear for the attachment of guy wires at intermediate points, a load-carrying member, and means for supporting said load-carrying member upon the tracks, said means comprising a side plate, 10 a wheel bearing carried by said side plate, a wheel journaled in said bearing and arranged to engage the mast track, and means for detachably securing the side plate to the load-carrying member.
- 15 6. An apparatus for handling building materials comprising a mast, laterally pro-
- jecting vertical tracks carried by said mast, a load-carrying member, and means for supporting said load-carrying member upon the tracks, said means comprising a rearwardly 20 projecting flange carried by the load-carrying member and provided with an open slot, a bearing sleeve arranged in the slot, portions carried by said bearing sleeve for detachable connection with the rearwardly- 25 projecting flange, a side plate carried by the bearing sleeve for detachable connection with the load-carrying member, and a wheel journaled in the bearing sleeve and arranged to engage the mast track.

WILLIAM H. INSLEY.
